US00D516731S

(12) **United States Design Patent** (10) Patent No.: **US D516,731 S**
Harris et al. (45) Date of Patent: **** Mar. 7, 2006**

(54) **THERMOCHEMICAL ACTIVATOR**

(75) Inventors: **Christa Harris**, Waukegan, IL (US);
Agnieszka Przeklasa, Mundelein, IL (US)

(73) Assignee: **Allegiance Corporation**, McGraw Park, IL (US)

(**) Term: **14 Years**

(21) Appl. No.: **29/195,554**

(22) Filed: **Dec. 11, 2003**

(51) LOC (8) Cl. **24-04**

(52) U.S. Cl. **D24/208**

(58) Field of Classification Search **422/245.1, 422/186; 62/4; 607/96, 108-113, 114; 383/901; 40/486; 446/369; 423/201; 126/263.04; 604/358, 604/385.01; 128/885; 428/596; D24/200, D24/206-208; D6/597-598, 601, 96**

(57) **CLAIM**

We claim the ornamental design for the thermochemical activator, as shown and described.

DESCRIPTION

FIG. 1 is an overall angled side view of the thermochemical activator according to the invention;
 FIG. 2 is a top view of the thermochemical activator;
 FIG. 3 is a bottom view of the thermochemical activator;
 FIG. 4 is a side view of the thermochemical activator;
 Fig. 5 is a side view of the opposing side of FIG. 4 of the thermochemical activator;
 FIG. 6 is an end view from the lobed portion of the thermochemical activator; and,
 FIG. 7 is an end view from the pointed end of the thermochemical activator.
